SCREW-ACTUATED VISE HAVING RELEASABLE NUT FOR QUICKLY OPENING OR CLOSING THE JAWS

Anthony M. Sasgen, Chicago, and Fred P. Hopfield, Elmwood Park, Ill., assignors to Grand Specialties Company, Chicago, Ill., a corporation of Illinois

Application November 30, 1945, Serial No. 631,962

3 Claims. (Cl. 81—36)

1

This invention relates to vises and particularly to vises of the character wherein a relatively rigid base and a movable clamping member have opposed clamping jaws thereon between which pieces of work may be secured.

In the production of vises of the character to which the present invention relates, it is essential that the elements of the vises be efficiently constructed and designed so as to attain maximum strength in such parts while avoiding the use of excessive amounts of material, and to enable this to be accomplished is an important object of the present invention.

Another object is to afford a novel vise of the aforementioned type wherein a movable jaw member is supported by, and may be quickly and easily adjusted relative to, a stationary jaw member in a novel and expeditious manner.

Other and further objects of the present invention will be apparent from the following description and claims as illustrated in the accompanying drawings which, by way of illustration show preferred embodiments and the principle thereof and what we now consider to be the best mode in which we have contemplated applying that principle. Other embodiments of the invention embodying the same or equivalent principle may be used and structural changes may be made as desired by those skilled in the art without departing from the present invention and the purview of the appended claims.

In the drawings,

Fig. 1 is a side elevational view of a vise embodying the features of the invention;

Fig. 2 is a front elevational view of the vise;

Fig. 3 is a vertical sectional view taken substantially along the line 3—3 of Fig. 1 but with parts broken away at the lower right hand corner to give a fragmentary sectional view of the vise mount;

Fig. 3A is an enlarged portion of Fig. 3 and is taken substantially on the line 3A—3A of Fig. 1;

Fig. 4 is a horizontal sectional view taken substantially along the line 4—4 of Fig. 1;

Fig. 5 is a horizontal sectional view taken substantially along the line 5—5 in Fig. 3;

Fig. 6 is a fragmental vertical sectional view taken substantially along the line 6—6 in Fig. 5;

Fig. 7 is a horizontal sectional view showing the mounting base which forms a part of the vise when it is desired to enable rotative adjustment of the vise, the view being taken substantially along the line 7—7 of Fig. 3; and

Fig. 8 is a front elevational view of the basic form of vise showing the same as it is mounted

2

when the body of the vise is to remain in a fixed position.

In the form chosen for disclosure in Figs. 1 to 8 the vise of the present invention is illustrated as comprising a main body 10 having a stationary jaw 11 formed thereon in an upstanding relationship and having a slide 12 movably mounted on the body 10 so that a movable jaw 13 carried on the slide 12 may be moved toward 10 and away from the stationary jaw 11. The movement of the slide 12 is effected by means including a screw device 14 that acts between the slide 12 and the body 10, and the body 10 is adapted to be mounted on a base 15 in such a manner 15 that the body may be adjusted about a vertical axis on the base 15 and may be secured in any adjusted rotative position by means including clamping screws 16. Under the present invention, the body 10 may be mounted for rotative 20 adjustment on the base 15, as shown in Figs. 1, 2 and 3, or may be directly mounted upon a work bench or the like in a fixed position as illustrated in Fig. 8.

The body 10 is constructed in the form of a 25 casting, which is elongated in a horizontal direction, and throughout the major portion of its length, the casting is formed by a pair of downwardly and outwardly sloping walls 20 that are best shown in Figs. 2 to 5, these walls being connected at their upper ends as shown at 20A in 30 Fig. 3 so that this main portion of the body takes an inverted V-shaped form. Adjacent its forward end, the casting has an upwardly extended arm 21 upon the upper end of which the 35 jaw 12 is formed. Just rearwardly of the arm portion 21, the casting is formed with a relatively wide and flat extension that affords an anvil 22, as shown in Figs. 1 and 3, that terminates at its rear end portion in a narrow end 22A.

40 At its forward end and beneath the arm 21 and the anvil 22, the casting that affords the body 10 is extended outwardly to afford a mounting portion 25 that is annular or circular in character and which terminates in a downwardly 45 extended flange 26 as will be evident in Fig. 3 of the drawings. The flange 26 is so located that it extends across and beneath, and is integrally connected to, the lower edges of the walls 20 and thus these flanges serve to reinforce the body 10. The mounting portion 25 has flat upper 50 surfaces 27 formed thereon at opposite sides of the lower ends of the walls 20, and it is in the areas thus provided that the fastening means such as the screw devices 16 are located. For 55 this purpose, a bore 28 is extended downwardly

through the mounting portion 25 and centrally of each of the flat surfaces 27 so that fastening devices such as the screw devices 16 may be extended through such bores 28 in a manner that will hereinafter be described in detail.

The slide 12 is also formed as a casting, and at its forward end this casting has an upstanding arm 30 at the upper end of which the movable jaw 13 is formed, and the casting extends rearwardly to provide an arm 12A that is slidably related to the body 10. In affording such slidable interrelationship of the arm 12A and the body 10, the arm 12A is formed so as to have two downwardly and outwardly extending walls 32 that are joined at their upper ends so as to be of a substantially inverted V-shaped form. The size of the arm 12A is such that this arm may extend inwardly and means are afforded on the casting or base 10 to afford a slideway for the arm 12A. Thus, as will be evident in Figs. 1, 3, 4 and 5, the casting that affords the base 10 has a pair of turned flanges 34 formed at the lower ends or edges of the walls 20 near the forward portions thereof, and the flanges 34 have bearing lugs 33 extended upwardly in a slight amount therefrom near the rear end thereof, as shown in Fig. 5. The forward ends of the walls 20 are joined together only near their lower edges, such joinder being accomplished by the mounting flange 26 at the two places where it extends beneath these walls, and adjacent the forward end of the walls 20 a transverse web 36 is associated with the flange 26 so as to afford bearing surfaces 37 on its upper surface. As will be evident in Fig. 5, the web 36 is formed so as to overlie the forward portion of the flange 26 so as to be supported by this flange, and the lower edges of each of the walls 32 of the arm 12A have longitudinally extending flat bearing surfaces 32A formed thereon which ride upon the bearing surfaces 35 and 37 that are thus provided in the base. The opposed bearing surfaces 32A and 35 and 37 thus position the slide or arm 12A in a vertical sense, and the slide is also engaged laterally so as to be guided in this respect. Thus the walls 20 are extended inwardly at their forward ends to afford flanges that have bearing surfaces 39 formed thereon, while at the rear ends of the flanges 34 and in alignment with the bearing surfaces 35, the walls 20 have inwardly extended flanges that afford bearing surfaces 40. Thus the arm or slide 12A is engaged at spaced points so as to be accurately guided, and in this respect it will be observed that the bearing surfaces 39 and 40 face inwardly and downwardly so as to maintain the slide against vertical displacement away from the bearing surfaces 35 or 37.

The screw device 16 whereby the slide 12 is actuated towards its clamped position is in the present case in the form of a screw 41 that has a retaining washer 42 near its forward end, and the forward end of the screw 41 is extended through an opening 43 in the forward portion of the slide 12 so that this forward end extends beyond the forward end of the casting that affords the slide 12. A head 44 is fixed on the extending end of the screw 41 by means such as a pin 45, and a cross bar 46 is provided in the head 44 whereby the screw 41 may be rotated. The washer 42 and the head 44 maintain the screw 41 in a fixed longitudinal position with respect to the slide 12, and means are provided in association with the body 10 whereby rotation of the screw 75

41 is effective to move the slide 12 in a clamping direction.

The screw 41 is extended rearwardly through a substantial portion of the slide 12 and is engaged throughout a substantial portion of its length by positioning surfaces 48 that are afforded on inwardly extended longitudinal ribs 49 that are formed on the inner surfaces of the walls 32 of the slide. These bearing surfaces 48, Fig. 3, are generally arcuate in form and are faced generally downwardly, and means are provided on the base to serve as a nut which engages the exposed lower face of the screw 41 so as to enable actuation of the slide 12A to be effected. The means that are thus utilized to cooperate with the screw 41 are of the general character disclosed in the copending Sasgen application Serial No. 603,979, filed July 9, 1945, now Patent No. 2,445,188, but it will be observed that such means are located in a different and more protected position in the present instance. Thus the means that are employed in the vise herein disclosed comprise a bell crank 55 that is medially pivoted at 56 on a pivot pin that extends between two forwardly extending lugs 57, such lugs being formed as forward extensions of the cross member 36. The bell crank 55 has one arm 55A that extends downwardly beyond the lugs 57 so as to afford an operating handle, while the other arm 55B of the bell crank 30 has screw threads 58 formed thereon for engagement with the downwardly facing surfaces of the threads of the screw 41. The bell crank 55 is normally urged in a counterclockwise direction, Fig. 6, by a spring 59 that acts between the arm 55B and the cross member 36, and this tends to engage the threads 58 with the screw 41. It will be observed that the point of engagement of the threads 58 with the screw 41 is located upwardly and rearwardly with respect to the pivotal axis 56 40 so that when the screw 41 is rotated in a clamping direction, the forces applied to the threads 58 will be in a forward direction such as will tend to more firmly engage the threads 58 with the screw 41, and the upwardly directed forces that are thus produced on the screw 41 are resisted by the downwardly facing bearing surfaces 48 that are formed on the ribs 49 of the slide. With the releasable nut that is thus provided, an operator of the vise may attain a quick clamping action in respect to a workpiece by first releasing the nut by means of the handle 55A, thus to enable the slide to be quickly withdrawn to an extent that is more than sufficient to enable the workpiece to be put in position between the jaws 11 and 13. Such withdrawing movement is assisted by a spring 60, Fig. 4, that is connected at its opposite ends to lugs 61 and 61A provided respectively on the rear end of the slide 12 and on one of the webs 34. The user allows the slide 12 to be drawn forwardly in a work disengaging direction by the spring 60 until the jaw 13 is withdrawn from the work piece, after which the handle 55 is released so as to engage the threads 58 of the nut with the threads of the screw 41, 50 the previous work piece is removed and a new work piece inserted in the desired position, and the vise may then be securely clamped by a relatively slight rotation of the screw 41 in a clamping direction. In this connection it will be observed that the threads 41 and 58 as embodied in the form shown in Figs. 1 to 8 are of square cross section, but if desired, the threads may be made of angular or standard form as disclosed in the aforesaid copending application.

The annular or circular mounting flange 26 is

adapted to be positioned either on the base 15, or directly on a work bench, as shown in Fig. 8 of the drawings, and when the flange 16 is placed directly on the surface of a work bench, the vise may be secured in a fixed position on the work bench by means such as cap screws 16B, Fig. 8, that are extended through the openings 28.

When the body of the vise is to be mounted for rotative adjustment about a vertical axis, the flange 26 is placed in position on an upwardly facing annular bearing surface 62 of the mounting base 15 so that the body 10 of the vise may be rotatively supported on this annular bearing surface 62. Inwardly of the bearing surface 62, an upstanding guide flange 63 is provided that is annular in character and is concentric with the bearing surface 62, and it will be observed in Fig. 3 of the drawings, that the base 15 is in the form of an annular and substantially vertical ring 15A that is extended inwardly at its upper edge as at flange 15B to afford the bearing surface 62 and the upstanding guide flange 63. At its innermost end, the horizontal flange 15B has a downwardly facing abutment surface 65 that is annular in character and this abutment surface serves as a part of the means whereby the base 10 of the vise is secured in any adjusted rotative position on the base 15. In accomplishing such securing of the body 10 on the base 15, an elongated rectangular clamping bar 66 is disposed beneath the flange 15B so that its opposite ends are located beneath the annular surface 65, and the clamping devices 16 are associated with the bar 66 so that the bar may be drawn upwardly into firm clamping engagement with the surface 65. In accomplishing this, the screw devices 16 are in the form of screws having enlarged heads 16A and these screws are extended downwardly through the bores 28 and are threaded into suitable threaded openings in the bar 66. The heads 16A of the screw devices 16 have cross bars 16B slidably mounted therein so that the screw devices 16 may be readily operated to clamp the cross bar 66 against the annular retaining surface 65. The base 15 is adapted to be secured in a fixed position on a bench or the like by cap screws 68 extended through lugs 69 that project radially from the flange 15A of the base 15 at spaced points thereabout.

With the construction that is thus afforded in the embodiment of the invention shown in Figs. 1 to 8, the vise may be constructed in a standard model that is adapted to be mounted on a work bench in a fixed position as shown in Fig. 8, or may be mounted for rotative adjustment by associating the base 10 with a mounting base 15 through the use of a clamping bar 66 and the screw devices 16. Thus the problem of inventory is materially simplified through the use of the present invention. It will also be evident that the vise of the present invention is extremely rugged in character in that the material that is utilized in the formation of the parts serves effectively to impart strength to the parts of the vise.

Thus, while we have illustrated and described the preferred embodiments of our invention, it is to be understood that these are capable of variation and modification and we therefore do not wish to be limited to the precise details set forth, but desire to avail ourselves of such changes and alternations as fall within the purview of the following claims.

We claim:

1. In a vise, a body having elongated walls arranged in an inverted V-shaped relationship and having internal bearing surfaces defining a slideway, means on a forward end of said body affording a stationary jaw, a mounting portion rigid with said body and connecting said walls at spaced points along their lower edges, a slide having a movable jaw thereon and having an arm formed in an inverted V-shaped cross section so as to be open along its lower edge, said arm being slidably mounted in said slideway for movement of said movable jaw toward and away from said stationary jaw, a clamping screw rotatably mounted so as to extend longitudinally into said inverted V-shaped portion of said slide and held against longitudinal displacement with respect to said slide, means affording opposed downwardly facing bearing surfaces within said slide and engaging upper surfaces of said screw, a pair of spaced lugs extended forwardly from a forward part of said mounting portion, and means constituting a releasable nut pivoted on a horizontal axis between said lugs and extended upwardly and rearwardly through the open lower edge of said arm so as to engage said clamping screw.
2. In a vise, a body having elongated walls arranged in an inverted V-shaped relationship and having internal bearing surfaces defining a slideway, means on a forward end of said body affording a stationary jaw, a mounting portion rigid with said body and connecting said walls at spaced points along their lower edges, a slide having a movable jaw thereon and having an arm formed in an inverted V-shaped cross section so as to be open along its lower edge, said arm being slidably mounted in said slideway for movement of said movable jaw toward and away from said stationary jaw, a clamping screw rotatably mounted so as to extend longitudinally into said inverted V-shaped portion of said slide and held against longitudinal displacement with respect to said slide, a pair of spaced lugs extended forwardly from a forward part of said mounting portion, and means constituting a releasable nut pivoted on a horizontal axis between said lugs and extended upwardly and rearwardly through the open lower edge of said arm so as to engage said clamping screw.
3. In a vise, a body having elongated walls arranged in an inverted V-shaped relationship, means on the forward end of said body affording a stationary jaw, a mounting member rigid with said body and having two portions connecting said walls at spaced points along their lower edges, an elongated web member mounted on one of said portions of said mounting member, means, including said web, mounted on said body member and affording upwardly facing bearing surfaces disposed in a common horizontal plane along the lower edge portions of said walls in spaced relation to each other, a slide having a movable jaw and having an arm comprising elongated walls arranged in an inverted V-shape so that said arm is open along its lower edge, said slide being slidably mounted in said body with the lower edge portions of said walls of said slide mounted on said bearing surfaces in said body member so that movement of said movable jaw toward and away from said stationary jaw may be effected, a clamping screw mounted longitudinally in said slide for rotative movement with respect thereto but held against longitudinal displacement with respect to said slide, and means comprising a releasable nut pivotally

mounted on said mounting member at the forward end portion of said body and extending upwardly and rearwardly through the open lower end of said slide, said nut having a forwardly projecting handle on the lower portion thereof for moving said nut into and out of engagement with said screw.
